AUTOMOBILE WASTE RECEPTACLE

Wilfrid J. Perreault, Manchester, N. H.

Application August 29, 1955, Serial No. 37,693

Term of patent 7 years

(Cl. D14—6)

Fig. 1 is a front perspective view of the automobile waste receptacle showing my new design; and

Fig. 2 is a side view of the automobile waste receptacle.

I claim:

The ornamental design for an automobile waste receptacle, as shown.
